(57) **CLAIM**

The ornamental design for an ultrasonic cleaner, as shown and described.

DESCRIPTION

FIG. 1 is a first perspective view of an ultrasonic cleaner showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the ultrasonic cleaner thereof, and,

FIG. 10 is another exploded view of the ultrasonic cleaner thereof.

The broken lines shown in the drawings depict portions of the ultrasonic cleaner that form no part of the claimed design.
